Isaac J. Wright, Elbridge, New York,
Letters Patent, Dated, February 3, 1836.

The sole right reserved in these Letters Patent and making part of the
same, containing a description in the words of the said Isaac J. Wright
himself of his improvement in the above cutting.

To all whom it may concern

Be it known that of Isaac J. Wright of Elbridge in the County
of Onondaga and State of New York have invented certain im-
provements in the construction of machines for cutting stone and
I do hereby declare that the following is a full and exact
description thereof:

The stone to be cut is placed in a trough in the
most easy and the trough differs in form from those generally em-
ployed, being most conveniently made out of two pieces of plank
joined together lengthwise at right angles, or at any angle
greater or less than a right angle as may be preferred. This
trough has a cutting knife at one end which is fixed on a
frame sliding up and down in grooves like a slide saw frame.
The knife consists of two cutting parts united together at the
middle, so as to form a right angle, or any angle greater or less than a right
angle as may be preferred. The angle of the trough points downward
and the angle of the knife upwards, the cutting edge being down-
wards, the gate or point which carries the knife may be moved
up and down by means of a lever, a treadle, a crank, or in any of the
known ways of producing such a motion. The free edge of the
trough is armed with iron or steel for the knife to cut against.
Both the knife and the trough may instead of being on the angular
shape described be made curvilinear, in which case it will be best
to make the curve a segment of a small circle at the middle cor-
responding with the angular point above mentioned. The ob-
ject will in either case, be equally well attained, the

object being, so to form the form the knife and the trough, that as the former comes down upon the straw, they shall concur in gathering and pressing it into a compact state. The same end may be partially attained by giving the described shape to the knife alone. I intend some device to prevent that part of the trough which is against the knife, by a short angular or curved piece, in the same form with the trough inverted for the purpose of keeping the upper portion of the straw more completely together whilst feeding. The feeding may be performed in any of the usual ways.

What I claim as my invention and wish to secure by Letters Patent is the angular or curved form of the knife as above described, either used with or without a trough similarly formed for the purpose set forth, and I do not claim the angular trough when used alone, the same having been previously employed, but without an angular or curved knife such as is herein described.
